[57] **CLAIM**

The ornamental design for an advertising signboard, as
shown and described.

DESCRIPTION

FIG. 1 is a perspective view of an advertising signboard
showing my new design;

FIG. 2 is a front elevational view thereof, with the rear
being a mirror image; and,

FIG. 3 is a side elevational view thereof, with the oppo-
site side being a mirror image.

FIG. 1

FIG. 2

FIG. 3
